(57) **CLAIM**

The ornamental design for an electric massaging chair, as
shown and described.

DESCRIPTION

FIG. 1 is a top and left front perspective view of an electric
massaging chair, showing our new design.

FIG. 2 is a left side elevational view thereof, the opposite
side view being a mirror image.

FIG. 3 is a front elevational view thereof.

FIG. 4 is a rear elevational view thereof.

FIG. 5 is a top plan view thereof.

FIG. 6 is a bottom plan view thereof; and,

FIG. 7 is a side elevational view thereof showing the state
where the back is raised and the leg rest is folded.
